[57] CLAIM

The ornamental design for a whirlpool bathtub or the like, as shown and described.

DESCRIPTION

FIG. 1 is a top, front perspective view of a whirlpool bathtub or the like showing my new design;

FIG. 2 is a top plan view thereof;

FIG. 3 is a front elevational view thereof;

FIG. 4 is a side elevational view thereof, the opposite side being a mirror image;

FIG. 5 is a rear elevational view thereof;

FIG. 6 is a bottom plan view thereof;

FIG. 7 is a cross-sectional view taken along line 7—7 of FIG. 1;

FIG. 8 is a cross-sectional view taken along line 8—8 of FIG. 1;

FIG. 9 is a cross-sectional view taken along line 9—9 of FIG. 2;

FIG. 10 is a cross-sectional view taken along line 10—10 of FIG. 2;

FIG. 11 is a top, front perspective view of a second embodiment of my new design;

FIG. 12 is a top plan view thereof;

FIG. 13 is a cross-sectional view taken along line 13—13 of FIG. 12;

FIG. 14 is a cross-sectional view taken along line 14—14 of FIG. 12.

The front, rear, and sides of the second embodiment are identical to those of the first embodiment.
